UNITED STATES PATENT OFFICE.

BARNETT W. GROVES, OF ST. PETERSBURG, FLORIDA.

COMBINED PAIL AND SPRINKLER.

1,353,650.

Specification of Letters Patent. Patented Sept. 21, 1920.

Application filed February 20, 1918. Serial No. 218,281.

To all whom it may concern:

Be it known that I, BARNETT W. GROVES, a citizen of the United States, residing at St. Petersburg, in the county of Pinellas and State of Florida, have invented certain new and useful Improvements in Combined Pails and Sprinklers; and I do hereby declare the following to be a full, clear, and exact description of the invention, such as 10 will enable others skilled in the art to which it appertains to make and use the same.

My invention relates to improvements in combined pails and sprinklers and particularly to that type used in spraying flowers 15 or the like and is so constructed as to permit it to be readily converted into a pail for other purposes.

A further object of the invention is to provide a pail equipped in its bottom with 20 a novel valve which controls the flow of water from the pail during its passage therefrom.

Another object of this invention is to provide a pail equipped with a novel sprinkler 25 head which may be readily detached to form the pail into a filling device capable of filling radiators or the like.

Another object of this invention is to provide a pail equipped in its bottom with a 30 sleeve in which is movably mounted a valve and having a sprinkler head adapted to be secured to or removed from the sleeve when desired, the valve being equipped with means for automatically controlling the 35 flow of water from the pail to the sprinkler head.

A further object of this invention is to provide a combined pail and sprinkler of this character, which will be simple, practical and comparatively inexpensive in construction and one that can be manufactured and sold at a low cost.

With these and other objects in view, the invention consists in the novel combination 45 and arrangement of parts hereinafter more fully described, and set forth in the claim hereto appended.

In the drawings:

Figure 1 is a side elevation of a combined 50 pail and sprinkler as made in accordance with this invention.

Fig. 2 is a vertical longitudinal sectional view through the same.

Fig. 3 is an enlarged vertical sectional

view taken through the valve and sprinkler head.

Fig. 4 is a vertical sectional view through the valve, illustrating it in open position.

Fig. 5 is a transverse sectional view taken through the valve.

Fig. 6 is a side elevation of the valve.

Like numerals of reference designate corresponding parts in all the figures of the drawings.

Referring to the drawings, the numeral 5 65 indicates the body of a pail having a bottom wall 6. A plurality of supporting legs 6' are secured to and depend from the bottom 6. It is to be understood that the pail may be of cylindrical formation in cross 70 section or of any other shape desired. The bottom 6 is provided centrally with an opening 7 in which a valve supporting sleeve 8 is secured. The valve supporting sleeve 8 is secured vertically within and to the wall 75 of the opening 7 and extends above and below the inner and outer faces of the bottom 6. The inner portion of the sleeve is provided with a plurality of relatively spaced vertically extending outlet openings 80 9.

A spider 9' has a hub 10, and formed integrally with the hub and radiating therefrom are a plurality of spaced arms 11. The terminals of the arms 11 are secured to 85 the wall of the sleeve, as illustrated. The spider is located in the plane of the wall of the opening 7 of the bottom 6 of the pail.

A valve 12 is located within the sleeve 8 and its exterior diameter is as great as the 90 interior diameter of the sleeve to snugly fit therein. The valve is adapted to normally rest upon the upper side of the spider and to close the openings 9 in the sleeve and thus close the communication between the sleeve 95 and pail body.

A top or cover 13 is secured to the inner upper end of the sleeve 8 and is provided centrally with an opening through which is slidably mounted a valve operating rod 14. 100 The valve operating rod 14 is extended through the valve 12 and opening in the hub 10 of the spider and well below the same. The lower end of the valve rod 14 is enlarged as at 15 to constitute a stop. The 105 valve 12 is secured to the valve rod 14 intermediate the ends thereof so that upon the lifting of the rod, the valve will be moved

bodily therewith until the stop 15 engages the hub 10 of the spider, thus limiting the upward movement and establishing a communication between the pail body and sleeve 5 through the openings 9.

The upper end of the valve rod terminates into an eye 16 through which one end of the flexible operating member 17 is connected. A coiled spring 18 surrounds the valve rod 14 and is located between the cover 13 and upper side of the valve 12. One end of the spring bears against the upper side of the valve 12 and its opposite end against the under side of the top or cover 13, and this spring normally tends to seat the valve against the spider to close the communication between the sleeve and pail through the opening 9.

The pail 5 is provided at diametrically opposite points with offset bosses 19, each of which has an aperture in which one end or terminal of an inverted U-shaped bail 20 is adapted to be secured. The upper end of the flexible valve operating member 17 is connected to the bail 20. The terminal of the flexible operating means has secured therein an operating ring 21 which may be readily grasped for raising the valve rod 14 and lifting the valve 12 from its engagement with the spider to permit the contents of the pail to flow out through the openings 9 into and out through the sleeve and bottom wall of the pail.

A sprinkling nozzle is designated in its entirety by the numeral 22 and comprises a perforated front wall 23 and an imperforated rear wall 24. Each wall is provided with side flanges 25 which constitute means whereby they may be removably connected together as at 26.

A cylindrical connecting member 27 is formed integrally with the rear wall 24 and at an angle thereto so as to permit it to be readily connected to the lower outer portion of the sleeve 8 to convert the pail into a sprinkling can.

It will be understood that, by virtue of the angular formation of the connecting member 27 with relation to the head or nozzle 22 when it is slidably fitted upon the lower depending portion of the sleeve 8, the nozzle head will be at an angle to the bottom wall 6 so as to constitute a sprinkling nozzle.

It will also be understood that the cylindrical connecting member 27 is of a diameter sufficient to permit it to be frictionally fitted upon the depending portion of the sleeve 8 so as to prevent of its accidental displacement therefrom.

It will be understood that the head 22 may be readily moved and the sleeve 8 may

have its lower end arranged in the radiator of an automobile so that it may be readily and quickly filled with water.

From the foregoing description taken in connection with the accompanying drawings, it will be readily apparent that the pail body 5 is first filled with water or the like and by grasping the flexible member 17 and pulling upwardly thereon, the rod 14 will be raised and due to the fact that the rod is connected to the valve 12 the valve will be lifted from its seat or engagement with the spider against the tension of the spring 18, thus establishing a communication between the sleeve and pail body through the medium of the openings 9. Immediately upon the releasing of the flexible member 17, the spring 18 will normally urge the valve back into its engagement with the spider and thus close this communication.

Having thus described my invention what I claim is:

A combined pail and sprinkler comprising a pail having an opening in its bottom wall, a sleeve secured in said opening and projecting above and below the bottom of said pail, the upper portion of said sleeve having inlet openings formed therein, a cap secured over the upper end of said sleeve, a spider secured in said sleeve in the same plane with the bottom wall of the pail and having a central opening and radially arranged outlet openings, a removable sprinkler member mounted on the lower end of said sleeve, a bail handle for said pail, a valve rod having a limited movement through the central opening of the spider and through the cover of the sleeve, a valve rigidly mounted on said valve rod, a flexible member connected with the upper end of said valve rod and with the bail handle of the pail, an operating ring secured in the upper portion of said flexible member whereby a finger may be inserted to raise the valve from position upon the spider without releasing the grip upon the bail handle of the pail, said valve when raised from the spider permitting the fluid from the pail to pass into and through the sleeve and through the openings of the spider, and means surrounding the valve rod between the valve and the cap of the sleeve to resiliently retain the valve in engagement with the spider.

In testimony whereof I affix my signature in presence of two witnesses.

BARNETT W. GROVES.
